UNITED STATES PATENT OFFICE

HERMAN H. BOETTCHER, OF BLUE EARTH, MINNESOTA

SCOOPING MACHINE

Application filed January 31, 1927. Serial No. 164,948.

This invention relates to a scooping machine, and has for its primary object a construction whereby articles such as beets may be effectively scooped from the ground irrespective of the characteristics of the soil or the relative positions of the beets upon the ground. This is an improvement of my Patent #1,723,462, granted to me under date of August 6, 1929.

10 An object of the invention is the construction of mechanisms that can be rotated and shifted without the necessity of stopping the operation of the machine as a whole.

Another object of the invention is the 15 provision of a novel construction of scoop structure that may be adjusted toward and away from the ground to be properly positioned with relation to the articles to be scooped.

20 A further object of my invention is the novel construction of shiftable mechanism having parts so arranged and designed that the scoop devices of the scoop construction may be shifted or adjusted during the continuous operation of the scoop construction.

Besides the above, my invention is distinguished in the novel construction of scooping mechanism and its relative arrangement with the elevators and the tilttable frame so 30 that articles such as beets may be effectively engaged, lifted and conveyed to a wagon or other form of vehicle traveling with the machine.

35 A feature of my invention is the novel construction of shifter which, upon slight adjustment, simultaneously and properly shifts the relative position of the scoops so as to properly perform their operations in accordance with the characteristics of the ground or surface worked upon.

With these and other objects in view, my invention will be better understood from the accompanying drawings, wherein:—

- 45 Figure 1 is a side elevation of the machine;
 Figure 2 is a top plan view;
 Figure 3 is a rear elevation;
 Figure 4 is a sectional view;
 Figure 5 is a diagrammatic view illustrating a portion of the shifting mechanism;

Figure 6 is a vertical sectional view on the line 6—6 of Figure 2;

Figure 7 is a sectional view on the line 7—7 of Figure 6;

Figure 8 is a sectional view on the line 8—8 of Figure 6;

Figure 9 is a detail sectional view of a modification of my invention;

Again referring to the drawings illustrating one of the many constructions of my invention, the numeral 1 designates the frame of the machine mounted upon the wheels 2 to assume a downwardly inclining position to have its forward end 3 supported by the rollers 4 in a manner that the frame may be raised or lowered or tilted for changing the relative position of the various mechanisms in a manner hereafter described.

To accomplish this result in a simplified manner, the rollers 4 are journaled in a fork 5 that is raised and lowered in the bearings 6 by the links 7 connected to the bell crank 8. This bell crank 8 is connected by a rod 9 to the control lever 10. My improved rotary scoop construction, indicated in its entirety by the numeral 11, is of an adjustable construction so as to be adjusted toward and away from the ground independently of or in conjunction with the tilttable movement of the frame. Thus it will be understood that the relative position of the scoop construction and the ground may be changed in either of two ways, namely by the raising or lowering of the frame through the medium of the rollers 4 or by adjusting the scoop construction independently of the frame.

My improved scoop construction of the rotary type comprises a drum 12 mounted on the shaft 13 that is journaled in the frame and driven in any suitable manner, such as by the chain and sprocket drive connection 14 directly connected to the axle 15 of the wheels 2 so that by the movement of the machine over the ground the scoop construction will be operated in unison with the movement of the wheels. This drum 12 has secured thereto a plurality of devices whereby articles such as beets may be scooped from the ground to be deposited in a predetermined position and then discharged into suitable

conveying mechanism, and one manner of accomplishing this desired result is illustrated in the drawings as consisting of a plurality of trays 16 secured to the drum 12 to extend 5 radially therefrom and illustrated as formed from a plurality of bars 17, the inner ends of which are riveted to the drum, as illustrated at 18, and the outer ends formed into bearings 19 for the purpose of supporting the shaft 20 10 for rotation.

To complete the tray, I provide the end plates 21. This construction provides a tray having a plurality of slots 22 through which is adapted to travel my improved construction of scoops now to be described. The scoops 23 each consists of a tine 24 fixed to its associated shaft 20 to project radially or laterally from the shaft so as to travel in a circular direction to engage an article and 20 deposit the same onto the tray in the passage of the tine through its associated slot. As the tines are arranged in group formation with relation to their associated trays, it will be appreciated that a relatively wide strip of 25 ground will be effectively acted upon by the scoop construction and the articles collected will be carried toward the tray and left thereupon in the passage of the tines through the slots.

30 Each shaft 20 has secured thereto a crank arm 25 that is pivotally connected to a projection 26 forming one of the elements of a novel construction of adjuster 27. This adjuster 27 includes a shifter 28 illustrated in 35 the form of a ring 29 having formed solid therewith all of the projections 26 so that upon shifting or movement of the ring 29, all of the shafts will be simultaneously adjusted for adjusting the tines secured thereto to 40 change the relation of the active tines passing over the ground for engagement with the beets or other articles. In other words, the adjuster is constructed to shift all of the tines to have the proper relative position in passing 45 into engagement with the article.

Particular attention is called to the fact that the ring 29 is eccentrically arranged with relation to the drum so that upon rotary movement of the drum the ring will control 50 movement of the tine to the extent of forcing the tines to travel in their individual circular paths in the proper timed relation to engage and pick up an article and deposit the same onto its associated tray to be dropped 55 onto conveying mechanism hereafter described. That is to say, as the tines are traveling upwardly in a clockwise direction they will support the articles in their movement toward the tray so that in the downward 60 movement of the tines in a clockwise direction the tines will pass through the slots of the trays for leaving articles on the trays to be discharged onto the elevating mechanism.

For the purpose of accurately and posi- 65 tively adjusting the ring 29, I provide the

rockable link 30 mounted on the main shaft 13 and provided with a plurality of arms 31 that form journals for the rollers 32 that directly engage the inner peripheral surfaces 33 of the ring. Thus the ring is provided with a bearing of a construction to bodily shift the ring relative to the drum for changing the angular position of the tines so as to properly pass over the ground and engage articles thereupon. This link 30 is shifted by the control rod 34 passing to the control lever 35 on the frame. 75

Particular attention is called to the fact that the relative positions of the trays are such that they form therebetween troughs 36 of the proper capacity to receive and support the articles in their travel, and for the purpose of properly supporting the articles so as not to interfere with the movement of the tines, the bars forming the tray may have associated therewith curved guards 37, as illustrated in Figure 9. 80

Associated with my improved rotary scoop construction is a novel arrangement of elevating mechanism so designed as to receive the articles in their gravitational movement from the trays and elevate the articles to a point to be discharged laterally from the machine into a wagon or other suitable vehicle. This mechanism in one of its forms consists of a delivering elevator 38 having one end portion 39 arranged contiguous to the rotary scoop construction and in close proximity to the traveling trays so that the articles on the trays may be discharged in a direction to gravitate onto the elevator 38 to travel upwardly and be deposited on the chute 40. The elevator 38 is driven directly off of the shaft 13 by the sprockets 41 and chain 42. The chute 40 conveys the articles by gravity onto a dump elevator 43 that is mounted to discharge laterally from the machine into a wagon 44 or other suitable form of vehicle. This elevator 43 has a drive connection 45 with the axle 15 and is illustrated as a series of shafts 46 having a beveled gear connection with each other, as illustrated at 47. 95

To complete the machine, I provide any suitable form of draft gear 48 with the driver's seat 49 positioned contiguous to the control levers 10 and 35 and the ordinary pawl and ratchet support 50 for the levers. 100

With a machine designed and constructed as heretofore described and illustrated in the drawings, the operator is able to very efficiently scoop up various articles such as beets and other vegetables and pass the same in a direction to be deposited into a waiting wagon or other vehicle, thus not only reducing the time of such operation but accomplishing the desired result with a minimum expenditure of power. As the machine travels over the ground, the various drive connections will function to simultaneously 110 115 120 125 130

operate the rotary scoop construction and elevators so that the operations may be continuous to provide a continuous flow of material into the waiting wagon. As my improved rotary scoop construction rotates, the tines will be periodically positioned, as illustrated in Figure 6, to scoop under the article to deposit the same on top of the tines to be carried to a position where the tines are capable of depositing the articles onto the trays. Due to the changes in the character and formation of the ground worked upon, it is a great advantage to be able to adjust the tines in their relative movements over the ground so as to assume the proper position to engage the articles and that is the reason for designing control mechanism that may adjust the position of the tines while the scoop construction is in operation. Upon movement of the rod 34 by its control lever, the link will be shifted for displacing the ring and thereby shift the position of the tines through their crank connection with the projections 26.

25 Of course, it will be understood that in the initial positioning of the mechanism the rollers 4 are adjusted for tilting the frame into its proper position and any finer adjustment is accomplished by shifting the rod 34. Therefore, I provide two constructions for adjusting the position of the scoop construction relative to the ground. As the articles are being lifted by the scoop construction, the trays will successively reach an inclined position to allow the articles to gravitate onto the elevators 38, which moves the articles to a position to be deposited into the chute 40 for passage onto the dumping elevator for final movement into the wagon.

40 It is, of course, to be understood that the scoop structure may be designed in various other manners than illustrated to be operated by my improved shifting mechanism and the shifting mechanism may be designed in various other manners to operate my improved scoop structure and, in fact, my improved rotary scoop construction may be arranged and connected to various other types of mechanism without departing from the spirit of the invention and, therefore, I do not desire to be limited in any manner except as set forth in the following claims.

I claim:—

1. A rotary scoop construction comprising a rotary support, a plurality of trays mounted on the support and projecting radially therefrom, a conveyor positioned to receive articles from the trays, and means for scooping up articles and depositing the same onto the trays, said means passing through the trays to facilitate the depositing of the articles on the trays.
2. A rotary scoop construction comprising a rotary support, means for rotating the support, trays secured to and projecting radially

ally from the support, scoops secured to the trays for movement toward and through the trays, and operating mechanism for the scoops.

3. A rotary scoop construction comprising a rotary support, means for rotating the support, trays secured to and projecting radially from the support, scoops secured to the trays for swinging movements toward and through the trays, and means controlling the position of the scoops relative to the ground in their passage thereover.

4. A rotary scoop construction comprising a rotary support, means for rotating the support, trays secured to and projecting radially from the support, scoops secured to the trays for swinging movements toward and through the trays, and means controlling the position of the scoops relative to the ground in their passage thereover, said means including a manually operated shifting member in permanent operative connection with all of the scoops.

5. A rotary scoop construction comprising operating mechanism including a rotary support, slotted trays secured to the rotary support and projecting radially therefrom, and scooping mechanism including a plurality of scoops secured to the trays to gather articles and then pass through the slots to deposit the articles on the trays.

6. A rotary scoop construction comprising a rotary support, a plurality of trays mounted on the support and projecting radially therefrom, scoops for gathering and depositing articles on the trays, and means for simultaneously shifting the positions of the scoops relative to the trays, the scoops being movable through the trays.

7. A rotary scoop construction comprising a rotary support, a plurality of trays mounted on the support and projecting radially therefrom, scoops for gathering and depositing articles on the trays, and means for simultaneously shifting the positions of the scoops relative to the trays without disturbing the rotation of said drum said scoops being movable through the trays.

8. In a machine of the character described, a drum, a plurality of trays projecting radially from the drum to form troughs therebetween, tines swingingly supported by the trays for movement through the same, and shiftable means connected to the tines to effect angular adjustment thereof relative to the trays.

9. In a machine of the character described, a drum, a plurality of trough structures projecting radially from the drum, tines mounted for movement into and out of the troughs through the same, and manually adjustable means for varying the movements of the tines.

10. In a scoop construction, a drum and a plurality of scoop structures mounted upon

and projecting radially from the drum, each consisting of a plurality of spaced bars, a shaft supported by the bars, tines secured to the shaft for passage between the bars, and means for operating the shaft.

5 11. In a scoop construction, a drum, a plurality of spaced bars projecting radially therefrom, tines secured to the bars for angular movement between the bars, and operating mechanism for simultaneously adjusting 10 all of the tines as a unit.

12. In a scoop construction, a drum, bars secured to and extending radially therefrom and in spaced relation, scooping mechanism including tines mounted for angular movement 15 between the bars, said bars having relative arrangement to provide troughs therebetween, and guards secured to and curving away from the associated bars.

20 13. In a scooping machine, a frame, a shaft journaled in the frame, means for driving the shaft, a drum secured to the shaft, a plurality of groups of relatively arranged bars secured to the drum in spaced relation, a shaft for each group of bars, a group of tines secured to each shaft for angular movement relative to and between the bars, a crank arm secured to each shaft, a single ring pivotally connected to all of the crank arms, a rockable link 25 mounted on said shaft and carrying a plurality of rollers engaging and forming a support for the ring, and manually operated means for rocking the link and thereby displacing said ring.

30 55 In testimony whereof I affix my signature.
HERMAN H. BOETTCHER.
